CLAIM

I claim the ornamental design for a universal remote and charging stand, of the present invention as shown and described.

DESCRIPTION

FIG. 1 is a front elevational view of a universal remote and charging stand of the present invention;

FIG. 2 is a rear elevational view of the universal remote and charging stand of FIG. 1.

FIG. 3 is a top view of the universal remote and charging stand as depicted in FIG. 1.

FIG. 4 is a bottom view of the universal remote and charging stand as depicted in FIG. 1.

FIG. 5 is a right side view of the universal remote and charging stand as depicted in FIG. 1.

FIG. 6 is a left side view of the universal remote and charging stand as depicted in FIG. 1; and,

FIG. 7 is an isometric view of the universal remote and charging stand as depicted in FIG. 1.

The power cord is shown broken away in order to indicate that a specific length of power cord forms no part of the claimed design.

The present design relates to universal remote and charging stand for use in the remote control of electronic devices such as television sets, DVD and CD players, video playback devices, and the like.
